FIG.15

FIG. 16

FIG. 17

FIG. 18

FIG. 19

FIG. 1 is a front view of a padlock showing my new design;

FIG. 2 is a rear view of the padlock of FIG. 1;

FIG. 3 is a bottom view of the padlock of FIG. 1;

FIG. 4 is a side view taken from the right side of FIG. 1 which is a mirror image of the side view taken from the left side of FIG. 1;

FIG. 5 is a top view of the padlock of FIG. 1;

FIG. 6 is a front view of a modification of a padlock showing my new design;

FIG. 7 is a side view taken from the right of FIG. 6 which is a mirror image of the side view taken from the left of FIG. 6;

FIG. 8 is a bottom view of the padlock of FIG. 6;

FIG. 9 is a top view of the padlock of FIG. 6;

FIG. 10 is a rear view of the padlock of FIG. 6;

FIG. 11 is a front view of a further modification of a padlock showing my new design;

FIG. 12 is a rear view of the padlock illustrated in FIG. 11;

FIG. 13 is a bottom view of the padlock illustrated in FIG. 11;

FIG. 14 is a side view taken from the right side of FIG. 11 which is a mirror image of the side view taken from the left side of FIG. 11;

FIG. 15 is a top view of the padlock illustrated in FIG. 11;

FIG. 16 is a front view of another modification of a padlock showing my new design and which is identical to the rear view of the padlock illustrated in FIG. 16;

FIG. 17 is a side view taken from the right side of FIG. 16 which is a mirror image of the side view taken from the left side of FIG. 16;

FIG. 18 is a bottom view of the padlock illustrated in FIG. 16; and

FIG. 19 is a top view of the padlock illustrated in FIG. 16.

I claim:

The ornamental design for a padlock, as shown and described.
